UNITED STATES PATENT OFFICE

2,317,268

PATTERN CONTROL FOR KNITTING MACHINES

Isaac H. C. Green, Pawtucket, R. I., assignor to
Hemphill Company, Central Falls, R. I., a corporation of Massachusetts

Application January 24, 1942, Serial No. 428,045

15 Claims. (Cl. 66--135)

This application concerns an invention in a means for controlling pattern means in circular, independent needle knitting machines. More specifically, the invention has to do with a unitary means adapted to regulate several other pattern devices on the machine, to conserve the pattern on each and to maintain proper timed relationship in the operation of each.

In the figures of drawing:

Fig. 1 is a side elevation of a typical hosiery frame to which the invention has been applied;

Fig. 2 is a plan view of such part of a machine of this type as is necessary for illustrating application of the invention to reverse plating, wrap stripe and wrap stripe shogging of varying controlling means;

Fig. 3 is a detail of ratcheting means for the wrap stripe shogging control;

Fig. 4 is a detail of the ratchet wheel and pawls for actuating the same as applied to the mechanism illustrated in Fig. 3;

Fig. 5 is a detail of the pattern chain and means cooperating therewith located at the back of the machine;

Fig. 6 is a detail view of certain levers through which the pattern variations as dictated by the chain are taken and transferred to other functioning elements of the machine;

Fig. 7 is a sectional view taken at the line 7—7, Fig. 6;

Fig. 8 is a view similar to Fig. 5 but showing that mechanism as seen from the opposite side;

Fig. 9 is another view of the mechanism of Figs. 5 and 8 but showing parts thereof as seen in plan;

Fig. 10 is a detail view of latching means for the wrap stripe and reverse plating actuating devices;

Figs. 11, 12 and 13 are further views similar to Fig. 8 but showing control for the ratcheting means which functions periodically to move the pattern chain at the back of the machine;

Figs. 14-19 are isometric views of chain links which are used in making up the complete chain;

Fig. 20 is a conventional view of part of a stocking showing one pattern to be produced by the novel mechanism of this case;

Fig. 21 is a diagrammatic representation of a small section of the pattern in Fig. 20 and showing certain specific details thereof;

In certain types of knitting machines such as circular, independent needle hosiery machines, rather complicated patterns are produced as effected by plating and reverse plating control and wrap striping means. The control for the wrap

striping means involves two separate mechanisms, one, that for needle selection, and the other, that for varying the position of the wrap stripe yarn feeding means itself so as to effect changes of pattern in that way, in other words, by so-called shogging.

The plating and reverse plating control may be of a type affecting needles as by deflecting them or, more preferably, may be of a type to act upon individual sinkers as in United States Patent No. 2,211,785.

Normally each of these particular pattern control means, that is, the plating and reverse plating, the wrap stripe needle selection control and the shogging control is separately actuated, although in a specific timed relationship, and normally no one of these is stopped during the production of a pattern except for the knitting of a heel or toe or some unpatterned part of the stocking being formed. That means that each of the pattern mechanisms starts at the initial point in a pattern for that particular stocking and continues in operation repeating its pattern as often as has been necessary depending upon the number of moves with which each of the individual controls was originally provided.

For example, 48 moves have been adopted as standard in the particular type of machine illustrated here so that after 48 individual racking or ratcheting movements of one of the drums, the pattern must be repeated. It is often desired to conserve pattern means by stopping it at intervals, the effect then being to extend the result of an independent and individual revolution of one of the pattern drums affecting any of the pattern phases above mentioned so that the scope thereof, insofar as size of figure goes, is considerably widened. That has been done, so far as known, only with a single independent drum.

No means has been devised which would periodically stop each of several independent pattern means and yet maintain timed relation such that each of the pattern phases would simultaneously be carried to termination and then be repeated in properly timed relationship. By means herein described the three separate pattern means are simultaneously started and stopped so that a pattern which is, of course, the result of the combined effect of all of these pattern means, would be conserved and greatly extended so that for any given number of steps in a pattern and number of moves of the various drums or other pattern means, a combined wrap stripe and reverse plating pattern may be knitted which will be of appreciably greater scope than would

have been possible by the mechanism as heretofore constructed and employed.

Now referring to Figs. 1, 2, 3 and 4, part of a hosiery knitter has been shown wherein a frame is indicated by numeral 1, main drive shaft at 2, cam shaft at 3, and in Fig. 2, a carrier ring 4 having the usual yarn feeding levers 5. The needles and the needle cylinder are not shown although the circular base 6 would support the usual cylinder and independently movable latch or other needles; preferably, the cylinder would be rotated by gearing from the shaft 2 driven by pulleys such as the pulley 7. In Fig. 2 a part of the wrap mechanism only is illustrated, the illustration being limited to central wrap spindle 8, collar 9 and a fork 10 which engages the collar to raise and lower it for the purpose of shogging the wrap yarn feeding fingers relatively to needles to which they feed their yarns. For a complete showing of such wrapping means, reference is made to United States Patents No. 1,702,608 and No. 2,146,750.

The needles (not shown) would have jacks under them provided with removable pattern butts all as shown in said United States Patent No. 2,146,750, and those jacks would serve to select such needles as were to be wrapped with the patterning threads according to the disposal of certain butts 11 on superimposed discs in a drum generally indicated by reference numeral 12. This drum 12 is rotatable about a center 13 and is ratcheted periodically by a pawl 14 engageable with teeth in a ratchet wheel 15, the latter being a functioning part of the drum assembly which rotates at the center 13. The number of teeth in the ratchet wheel 15 is preferably the same as the original number of butts 11 in any one disc on the drum. The pawl 14 is connected as shown in Fig. 2 at a pivot point 16 to a bell crank lever 17 in turn pivoted at 18 at the upper surface of the circular base. This lever 17 is connected to the link 19 which extends toward the back of the machine and connects to the upper end of a bar 20, Fig. 3. This bar 20 similar to bar 21, Fig. 1, pivots at a common pivot point 22 with the latter mentioned bar and each is guided within an appropriate slot adjacent its upper end and in the extension 23 bolted to the back of the circular base.

The 104-tooth gear 24 is rotatable about the center 25—the usual construction in machines of this type. This 104-tooth gear has at either side thereof certain cam engaging rollers, one of which is illustrated at 26, these varying in number according to the frequency with which the cam drum or drums are to be ratcheted. The 104-tooth gear makes one revolution for every four turns of the needle cylinder and thus, if a ratcheting movement is desired every revolution, there must be four rollers such as rollers 26. By that it is meant that there must be four such rollers for each bar 20 or 21. Bar 21 has a plate 27 attached thereto having a cam edge or surface 28 to be contacted by the rollers 26. Every time one of said rollers engages the cam surface on the plate 27, for example, bar 21 will be swung about its pivot 22. A similar plate (not shown) is provided for the bar 20 and that is engaged and the bar 20 actuated in a similar manner by other cam engaging rollers at the opposite face of the gear 24. A spring 29, Fig. 2, is connected in such a manner as to maintain the bar 20 in forward position or in position for the pawl 14 to engage another tooth. The drum 13 is frictioned as usual to prevent overrunning or unin-

tentional movement. The butts 11 are broken off according to the particular pattern desired and these butts work upon a series of plungers or levers which in turn engage butts on jacks thereby imparting to the jacks and their needles the desired movement.

Now referring to Figs. 1 and 2, a second pattern drum 30, similar to the drum 12, has discs with butts 31, the said butts 31 being engageable with a toe 32 of lever 33. There are a plurality of discs having butts 31 and for each of these discs, a lever 33. The series of levers 33 are pivoted at 34 in a bracket 35 disposed at such a level or height as to allow the ends of the levers 33 opposite the toes 32 to engage a series of plungers 36, there being one such plunger for each lever. These plungers are maintained in alignment so that ends thereof adjacent the sinker cam cap generally indicated by numeral 37, may engage butts at the respective levels on sinker jacks (not shown) the mechanism illustrated at this point is that of a 25-step sinker reverse plating selecting means and is illustrated in detail in United States Patent No. 2,211,785. The drum 30 pivots at 38 above plates 39 and 40 attached above a supporting casting 41. This drum 30 also has a ratchet wheel 42 by means of which it is periodically moved, the general construction of said ratchet wheel 42 being the same as that of the wheel 15. Drum 30 is frictioned by the usual frictioning means.

Drum 30 is ratcheted by means of pawls such as the pawl 43 pivoted at 44 to a plate 45 the latter also oscillating about the point 38. Springs 46 maintain these pawls in engagement with the teeth on wheel 42. Plate 45 has a projecting arm 47 to which is pivoted at 48 a link 49 which in turn attaches at 50 to a lever 51 pivoted at 52 on an extension 53 to the plate 40. Lever 51 at its opposite end has connected at 54 a link 55 attached at 56 to the upper end of bar 21. A spring maintains the mechanism in one position and contact of rollers 26 with the cam surface of plate 27 imparts movement in the opposite. The oscillating movement set up serves to rotate drum 30 and thereby impart patterning movements to the plungers 36 which in turn affect the positions of sinkers, the plating and reverse plating control thus being effected.

A mechanism including the lever 56' and connected levers and links serve to stop the ratcheting of the drum 30 during desired times as in knitting a heel or toe. Other means provides for imparting double tooth movements to the drum and for retiming it. These are well known in the art and described in United States Patent No. 2,052,777.

On the shaft 57, Figs. 1, 2, 3 and 4, is fixed another ratchet wheel 58, said shaft also having fixed thereto drums 59 and 60. These drums may have series of pattern projections 61 which serve to impart selective movements to various parts of the machine. For example, one row of such projections 61 (only three such projections being shown) serves to control the shogging or other movement of the wrap stripe mechanism. The said projections engage beneath a follower 62 attached midway of a lever 63 pivoted at 64 to an upstanding post 65 at the back of the machine. A flat plate 66 at the outer end of said lever 63 engages beneath one end of a lever 67 pivoted on a bracket 68 and also connected to the outer end of lever 69, the opposite end of which comprises the fork 10.

At certain times a change of pattern is contem-

plated and for that purpose there will be more than the single row of pattern projections 61. The follower 62 is shifted automatically for the purpose of deriving its pattern selections from any desired one of said rows. A spring 70 normally urges the hub 71 of the lever 63 in one direction along the pivot shaft 64 upon which lever 63 is free to swing. There is another lever 72 having a hub 73 which is also free to swing on this shaft 64 and spring 70 is under compression as it is confined between hub 73 and collar 74 fixed at the end of the shaft.

The bell crank lever having arms 75 and 76 pivots on an extension 77 of bracket 78 and to the arm 75 is connected a link 79 which also attaches at pin 80 to move the hub 71. The other arm 76 of the bell crank lever connects to a link 81 deriving movement through connection to a pattern drum (not shown). By movements of the bell crank lever and under influence of spring 70, the hub 71 and thus lever 63 and follower 62 are moved so that they will be affected by any desired row of pattern projections such as projections 61.

The ratchet wheel 58 is periodically moved by pawls 82 and 83. These pawls are projected at the extended arm 84 of a plate 85 also free to move about the shaft 57. The plate also has a downwardly disposed arm 86 to which is attached one end of a short link 87 connecting at its other end to a pivot 88 at the upper end of bar 20.

Springs 89 urge the pawls into engagement with teeth on the ratchet wheel. As shown in Fig. 4 this wheel has one short tooth 90, while a plate 91, also freely pivotable about shaft 57, serves to move the pawl 83 outwardly just far enough so that it will not engage this short tooth. So long as said pawl 83 is held out, Fig. 4, the ratcheting of the wheel and movement of the drums 59 and 60 will be discontinued. This plate 91 has an extending arm 92 which connects at a pivot 93 to a link 94 shown in Figs. 1, 2 and 3 and extending downwardly to connect to a lever 95 pivoted at 96 to the bracket or holder 97 at the side of the frame. The lever 95 is bent as at 98 and has a follower or toe 99 which engages upon a cam 100 fixed on cam drum 101 on the main cam shaft. When this cam 100 engages follower 99 as in Fig. 1, it will pull down on the link 94 swinging the plate 91 from the position of Fig. 3 to that of Fig. 4. In other words, the cam 100 controls pawl 83 so as to discontinue movement of pattern drums 59 and 60 as for retiming or for any other desired purpose.

Referring to Figs. 2 and 9, there is a special means by which ratcheting of the drum 12 and of the shaft 64 may be limited to one or to two teeth. A latch 102 pivots at 103 and connects by means of a link 104 to a bell crank lever 105 at the back of the machine. This lever 105 also connects to a vertically disposed link 106 which is also pivoted at its upper end to the lever 72, Fig. 2. This lever 72 has a cam follower (not shown) which is engaged by a cam 107 on the drum 60 and by means of the mechanism just referred to briefly which has been a part of Banner 19-step wrap stripe machines for some time, the ratcheting movements from the bar 20 are discontinued when that bar is held in its rearmost position by the latch 102.

Now referring to Figs. 5-13, the pattern chain and associated parts which simultaneously and during production of a pattern start and stop both reverse plating and wrap striping functions will be described. A bracket 108 extends from

the back of the machine and has fixed at 109 a shaft upon which are free to turn the ratchet wheel 110 and a sprocket 111. A friction means 112 prevents unintentional movement of either the sprocket or ratchet wheel which are really connected so as to move as a unit. The sprocket carries a chain 113 made up of any number of pattern links such as may be found necessary to impart the desired pattern movements. These links are differentiated in a manner later to be described.

The central pivot 109 has freely movable thereon an arm 114 which has pawls 115 and 116 pivoted at 117 for engagement with the teeth of the ratchet wheel 110. Springs 118 serve to keep the pawls in engagement with the said ratchet wheel teeth. The arm 114 has an adjustable, two piece link 119 connected at 120 and attached at its other end as at 121 to a lever 122 pivoted at 123 to the extension bracket 108. This lever 122 engages by a joint 124 to a second lever 125 pivoted at 126 and which in turn is contacted by a series of rollers 127 adjacent the outer periphery of the 104-tooth gear. In this particular instance there are four such rollers so that there is a ratcheting movement of the pattern chain each revolution of the machine cylinder, or one for every course knitted. There may be fewer of these rollers 127 in some instances where it is not desired to provide control of the chain for each course. A spring 128 causes return movement of the pawls to engage another tooth.

In Figs. 11, 12 and 13 different positions of the pawls are shown as affected by a retiming control. A plate 129 is also pivoted at 109 and has an arm 130 extending at the other side of the pivot. This plate 129 has a cam edge with the surfaces 131 and 132. This cam edge works upon a roller 133 on pawl 115. By means of the cam surface 132, roller 133 and pawl 115 are pushed away from engagement with the ratchet wheel teeth. In the heel, the pattern is simply discontinued and the cam surface 132 is effective as just described to stop ratcheting of the chain, see Figs. 5 and 12.

To move the plate 129, a link 135 is connected at the end of the arm 130 and continues upwardly as in Fig. 1 to connect at 136 at one end of a lever 137 pivoted at 138 on the upstanding post 139. A second link 140 connects at the other end of lever 137 and extends down at the side of the machine to attach at one end of a lever 141 pivoted at 142 on bracket 143 at the side of the machine frame. This lever 141 has a toe 144 which is engaged by cams such as the cams 145 and 146 on drum 101.

The plate 129 is slotted as at 147 so that the connection 120 extending out from arm 114 may project through said slot and that the plate and the arm may work separately without interference. When the toe 144 is in the position of Fig. 1, that is, on the drum, the plate assumes the position of Fig. 11, in that position neither cam surface 131 nor 132 is effective to lift the pawl. In the heel cam 145 will engage toe 144 of lever 141 and will move the plate to the position of Fig. 12. At that time the cam surface 132 will be effective upon roll 133 to raise pawl 115 well away from the ratchet wheel teeth, also pawl 115 will engage pin 134 and move the pawl 116 far enough away so that it will not contact any of the teeth. When the toe 144 drops from cam 146, the parts will return to the position of Fig. 11 and the pattern will continue and knit throughout the foot of the stocking.

In the toe it is desired to discontinue the pattern, also to retime the chain. To do that the pattern is stopped by appropriate links on the chain or by control from the main cam shaft, while the chain continues to move until a definite point thereon is reached. Cam 145 will engage beneath toe 144 and will move the plate 129 so that cam surface 131 will engage beneath roller 133 lifting pawl 115 as in Fig. 13. However, that does not render pawl 116 inactive. The pawl 116 will continue to ratchet the chain until a special link, Fig. 17, having a lug 147 is encountered. Then that special lug will engage beneath a roller 148 on the pawl 116, see Fig. 5, and will lift it away from the ratchet wheel so that both the wheel and the chain sprocket will stop. That condition prevails until it is desired to start a pattern again at which time the toe 144 of lever 141 will drop from the cam and will allow pawl 115 to start the chain and of course when that is done, the special lug 147 will move out from under roller 148 so that both pawls become active.

As in Figs. 14-19, each of the chain links 149 has one or more lugs or projections 150 at the side thereof opposite the special lug 147 mentioned above. These lugs 150 may occupy the different positions illustrated, or there may be no lug at all as in Fig. 16.

These lugs 150 are adapted as shown in Figs. 5, 6 or 7, to engage beneath a toe 151 on a lever 152 pivoted at 153 on the extension 154 to bracket 108. Above this lever 152 are two bell crank levers having horizontally disposed arms 155 and 156. These pivot at 157 on angular piece 158 and have springs 159 tending to draw them downwardly so that they bear against the top of the lever 152 and maintain toe 151 down on the chain except when it is raised by one of the lugs.

The bell crank levers have more or less vertically disposed arms 160 and 161 which attach to the links 162 at 163. Link 162 connects to a latch 164 pivoted at 165 while the link 163 connects to latch 166 pivoted at 167. Each of these pivots at the said latches 164 and 166 is about midway of the latch so that when links 162 and 163 push against them upon being moved to the left, Fig. 9, the bars 20 or 21, as the case may be, will be locked in position as in Fig. 10. Of course, that occurs whenever a lug 150 moves to the position of Fig. 6 swinging the bell crank levers against the tension of spring 159. The actual height of a chain lug is such that there would be an overtravel of the latching means except for springs 168 and 169 which merely elongate since the connections for these links 162 and 163 provide for sliding.

When the toe 151 is not held on a lug 150 the latches 164 and 166 will be moved to the positions they occupy in Fig. 9, but only upon a slight rearward movement of the bars 20 and 21. It can be seen that the latches have lips 170 and 171 which engage the upper ends of the bars and prevents unlatching until one of the rollers on the 104-tooth gear causes a slight rearward movement of the said bars so that under the fairly heavy springs, the bars and attendant mechanisms do not snap from one position to the extreme position, possibly causing damage.

In Fig. 20 a stocking is shown wherein there is a pattern formed by plating, reverse plating and by wrap striping. This stocking has a top 172 which may be the usual rib top or an elastic top of any desired form. The leg portion 173 has

what we will call areas of plating such as 174 and wherein the cross-hatching is by vertical lines, and adjacent areas 175 which represent reverse plated fabric, the latter being characterized by horizontal hatching. The diagonal lines 176 are wrap stripe lines and it is to be understood that preferably, the plating and reverse plating are from different colored yarns as is commonly understood in the art, while the wrap stripe lines are from still another color of yarn. The particular pattern here is what is generally termed an Argyle pattern. Of course, the stocking has the usual heel and toe.

In order to produce a pattern such as this wherein the figured areas are very large, the expedient of starting and stopping the pattern drums in such a manner as to conserve their moves is most desirable. As shown in Fig. 21, a small section of fabric 177 corresponding to the same area at the intersection of two wrap stripe lines, Fig. 20, has the wrap stripe lines such as the line 176 made up of wrap stitches in non-adjacent wales and courses. By conserving or holding back the pattern, it is possible to do this wrapping in non-adjacent courses and thus to open up or enlarge the area included within diagonal lines produced by the wrapping mechanism.

If the wrapping were to be continued at each course, one revolution of the drum 12 would make it necessary after a relatively short time to repeat the pattern. By stopping the drum, and at the same time stopping the other drum 30 and those on the shaft 57, the entire pattern is correspondingly enlarged and yet the same simple pattern controlling means may be employed. Of course, only one particular pattern has been illustrated here, but the invention is adaptable to all practical variations of pattern size or contour and it is to be understood that one skilled in the art would have no difficulty in setting up a pattern chain adapted to bring about the desired holding of the pattern and prolonging its effect so that for any particular number of steps originally provided in a pattern, corresponding increases in the effect thereof may be realized.

In operation it may be assumed that at the start of a pattern as in the leg of a stocking, the bars 20 and 21 will be periodically moved as the 104-tooth gear rotates while the drum 12 for the wrap stripe pattern 30 for the reverse plating control and 59 and 60 for controlling the relative shogging or placement of the wrap stripe feeding means, will be ratcheted. Now without further control, this ratcheting of said drums would tend to continue at some predetermined rate depending upon the number of rollers 26 on the gear 24, Fig. 1. Then depending upon the number of butts or other pattern conformations on the several drums, the pattern would be repeated at fixed intervals.

Depending upon the set-up of the pattern chain, lugs 150 will periodically move lever 152 so that the bell crank levers bearing thereon and connected to the levers 164 and 166 will be caused to hold the bars 20 and 21 or to release them according to the dictates of the particular pattern. When released the pattern will progress, and when latched, will be held back so that the pattern will be repeated at the same move of the drum or drums for a predetermined number of courses. When it is desired to stop the patterning entirely the ratcheting control for the several pattern drums is as usual taken from the main cam shaft. However, the chain is also

to be stopped at that time and for that purpose the cam 145 will act upon mechanism described in Figs. 1, 11, 12 and 13, to move both pawls 115 and 116 out of engagement with teeth on the ratchet wheel. For retiming the chain as at the knitting of a toe and preparatory to starting off in another stocking, pawl 115 is moved away from active engagement with ratchet wheel teeth but movement of the chain continues until the link having special lug 147 gets around to a position in which it will engage roller 148 on pawl 116 raising the pawl and thereby stopping the movement of the chain. The other pattern drums will have been retimed in a manner now known so that the entire pattern may start off in proper timed relationship at the desired point in the next knitted article.

The invention has been described by reference to one particular embodiment of the same, but it is to be understood that modifications may be resorted to and that the scope of the invention is limited only as defined in the appended claims.

I claim:

1. In a knitting machine the combination of knitting instrumentalities and means for feeding yarns to be knitted in patterned relationship by said instrumentalities, pattern means operable independently and independently functioning throughout a plurality of courses of knitting to impart separate patterning movements to the instrumentalities for the purpose of causing repeated pattern figures to be knitted and another pattern means functioning upon the said first mentioned pattern means to start and stop them simultaneously at any desired course or courses throughout the pattern and to maintain timed relationship thereof.

2. In a knitting machine the combination of knitting instrumentalities and means for feeding yarns to be knitted in patterned relationship by said instrumentalities, pattern means including control for some of said instrumentalities to select them for plating and reverse plating yarns and another pattern means for selecting knitting instrumentalities to receive a wrap stripe yarn or yarns, and a separate pattern means functioning upon the said pattern means for controlling plating and reverse plating and that for controlling selection of instrumentalities to receive wrap stripe yarns, so constructed and operable as simultaneously to start and stop said means at any desired course or courses throughout the knitting of a pattern and to maintain timed relationship thereof.

3. In a knitting machine the combination of knitting instrumentalities including needles and sinkers and means for feeding yarns to said instrumentalities and for feeding wrap stripe yarns thereto, pattern means periodically movable for controlling said sinkers to vary the plating relationship of said first mentioned yarns and another pattern means separately operable for selecting means to receive said wrap stripe yarns, another pattern means including a periodically movable pattern element with different pattern conformations thereon and means controlled thereby for causing the starting and stopping of said first mentioned pattern means simultaneously in any desired course or courses throughout the knitting of a pattern and maintaining timed relation thereof.

4. In a knitting machine the combination of knitting instrumentalities including needles and sinkers and means for feeding yarns to said instrumentalities and for feeding wrap stripe yarns

- thereto, pattern means periodically movable for controlling said sinkers to vary the plating relationship of said first mentioned yarns and another pattern means separately operable for selecting means to receive said wrap stripe yarns, another pattern means including a periodically movable pattern element with different pattern conformations thereon and means controlled thereby for causing the starting and stopping of said first mentioned pattern means simultaneously in any desired course or courses, throughout the knitting of a pattern and maintaining timed relation thereof and means for retiming said last mentioned pattern element.
5. In a knitting machine the combination of knitting instrumentalities including needles and sinkers and means for feeding yarns to said instrumentalities and for feeding wrap stripe yarns thereto, pattern means periodically movable for controlling said sinkers to vary the plating relationship of said first mentioned yarns, other pattern means separately operable for selecting needles to receive said wrap stripe yarns and a third pattern means for varying the feeding of said wrap stripe yarns, and a separate pattern means periodically movable for simultaneously at any desired course or courses throughout the knitting of a pattern starting and stopping each of the independent pattern means and for maintaining timed relationship between them.
6. In a knitting machine the combination of knitting instrumentalities including needles and sinkers and means for feeding yarns to said instrumentalities and other means for feeding wrap stripe yarns thereto and for shogging said wrap stripe yarns to be fed in different relationship relatively to cooperating instrumentalities, pattern means including three separate pattern drums for affecting the instrumentalities so as to vary the plating and reverse plating, the selection of instrumentalities to receive wrap stripe yarns and the shogging of the wrap stripe yarn feeding means, ratcheting means for periodically progressing each of said pattern drums above mentioned, and another pattern device including a periodically movable pattern element with different pattern conformations thereon and means affected by said conformations operable at any desired course or courses in the knitting of a pattern for simultaneously stopping said pattern drums and for simultaneously allowing the starting thereof.
7. In a knitting machine the combination of knitting instrumentalities including needles and sinkers and means for feeding yarns to said instrumentalities and other means for feeding wrap stripe yarns thereto and for shogging said wrap stripe yarns to be fed in different relationship relatively to cooperating instrumentalities, pattern means including three separate pattern drums for affecting the instrumentalities so as to vary the plating and reverse plating, the selection of instrumentalities to receive wrap stripe yarns and the shogging of the wrap stripe yarn feeding means, ratcheting means for periodically progressing each of said pattern drums above mentioned, and another pattern device including a periodically movable pattern element including a chain with different pattern conformations thereon and means affected by said conformations operable at any desired course or courses in the knitting of a pattern for simultaneously stopping said pattern drums and for simultaneously allowing the starting thereof.
8. In a knitting machine the combination of

knitting instrumentalities including needles and sinkers and means for feeding yarns to said instrumentalities and other means for feeding wrap stripe yarns thereto and for shogging said wrap stripe yarns to be fed in different relationship relatively to cooperating instrumentalities, pattern means including three separate pattern drums for affecting the instrumentalities so as to vary the plating and reverse plating, the selection of instrumentalities to receive wrap stripe yarns and the shogging of the wrap stripe yarn feeding means, ratcheting means for periodically progressing each of said pattern drums above mentioned, and another pattern device including a periodically movable pattern element and a chain with different pattern conformations thereon and means operable at any desired course or courses during the knitting of a pattern affected by said conformations for simultaneously stopping said pattern drums and for simultaneously allowing the starting thereof and means for retiming said chain.

9. In a knitting machine the combination of independent pattern means and actuating means therefor including ratchet wheels, pawls and means for moving said pawls independently so as to ratchet each of the pattern means once during each course of knitting, and another pattern element periodically movable and having connected between it and the means for moving said pawls, devices whereby the movements of the pawls may be stopped or started simultaneously and at any desired course or courses in the knitting of a pattern thereby to maintain timed relationship between the movements of said independently movable pattern means.

10. In a knitting machine the combination of knitting instrumentalities and means for feeding yarns to be knitted in patterned relationship by said instrumentalities, pattern means operable independently and functioning independently, but at a predetermined timed relationship throughout the knitting of a plurality of courses, to impart patterning movements to the instrumentalities in the knitting of a pattern effected by combined action upon more than one type of instrumentality thereby to cause repeated patterned figures to be knitted, and a controlling means constituting a separate and independent pattern device functioning to stop both of said means for imparting patterning movements simultaneously and at any desired course or courses in said plurality of patterned courses and to start said means simultaneously at any course or courses therein.

11. In a knitting machine the combination of knitting instrumentalities and means for feeding yarns to be knitted in patterned relationship by said instrumentalities, pattern means for controlling some of said instrumentalities to select and cause them to knit plated and reverse plated stitches, another pattern means for selecting others of said instrumentalities to cause them to receive and to knit wrap stripe yarns, a separate pattern means for controlling the pattern means effecting plating and reverse plating and wrap striping, the latter including a periodically movable pattern element and connections affected thereby and leading therefrom to cause the first mentioned pattern means to be stopped simultaneously at any desired course or courses throughout the knitting of a patterned area and to start said pattern means at any desired courses in that patterned area.

12. In a knitting machine the combination of

knitting instrumentalities and means for feeding yarns to be knitted in patterned relationship by said instrumentalities, a pattern means operable upon some of said instrumentalities for selecting them to determine the knitting of plated and reverse plated stitches, a second pattern means operable upon others of said instrumentalities for causing them to receive wrap striping yarns and to knit said yarns in plated relationship to the other yarns, a separate and independent pattern controlling means including a pattern chain with pattern conformations spaced thereon, ratcheting means for moving said chain periodically and connections operable upon contact with conformations on said chain for controlling latches to stop the movement of the first and second mentioned pattern means simultaneously at any desired course or courses throughout the knitting of a patterned area and other means for controlling the movements of said chain to retime it at the completion of knitting a complete knitted article.

13. In a knitting machine the combination of knitting instrumentalities and means for feeding yarns to be knitted in plating relationship by said instrumentalities, a pattern means operable on some of said instrumentalities for selecting them to determine the knitting of plated and reverse plated stitches, a second pattern means operable upon others of said instrumentalities for causing them to receive wrap striping yarns and to knit said yarns in plated relationship to the other yarns, a separate and independent pattern controlling means which includes a pattern chain with pattern conformations thereon, ratcheting means for moving said chain periodically, means affected by the conformations on said chain and connections leading therefrom to the first mentioned pattern means for stopping movement of said pattern means, the construction being such that the said separate and independent pattern controlling means may stop the first mentioned pattern means at any course or plurality of courses throughout a patterned area and may permit starting of said pattern means at any course or courses therein, and means to retime the said chain after the knitting of a complete knitted article.

14. In a knitting machine the combination of knitting instrumentalities and means for feeding yarns to be knitted in patterned relationship by said instrumentalities, pattern means operable independently and functioning independently, but at a predetermined timed relationship throughout the knitting of a plurality of courses, to impart patterning movement to the instrumentalities in the knitting of a pattern effected by combined action upon more than one type of instrumentality thereby to cause repeated patterned figures to be formed in the fabric, actuating means for each of the above mentioned pattern means and a latch, one for each of the actuating means, a controlling means constituting a separate and independent pattern device and connections leading therefrom to the latches for causing the stopping of each of the pattern actuating means, the construction being such that each latch can be disengaged only when the actuating means has been moved in a direction such that the latch is free from the said means.

15. In a knitting machine the combination of knitting instrumentalities and means for feeding yarns to be knitted in patterned relationship by said instrumentalities, pattern means operable independently and functioning independent-

ly, but at a predetermined timed relationship throughout the knitting of a plurality of courses, to impart patterning movement to the instrumentalities in the knitting of a pattern effected by combined action upon more than one type of instrumentality thereby to cause repeated patterned figures to be formed in the fabric, actuating means for each of the above mentioned pattern means and a latch, one for each of the actuating means, a controlling means constituting a separate and independent pattern device

10

and connections leading therefrom to the latches for causing the stopping of each of the pattern actuating means, the construction being such that the latches are released so as simultaneously to start the knitting of the combined pattern and then are again caused to engage the pattern actuating means so as to stop the pattern at any desired course or courses throughout the knitting of a patterned area.

ISAAC H. C. GREEN.

CERTIFICATE OF CORRECTION.

Patent No. 2,317,268.

April 20, 1943.

ISAAC H. C. GREEN.

It is hereby certified that error appears in the printed specification of the above numbered patent requiring correction as follows: Page 5, second column, line 11, claim 4, for "in" read --at--; lines 27 and 28, claim 5, strike out "at any desired course or courses throughout the knitting of a pattern" and insert the same after "means", line 29, same claim; and that the said Letters Patent should be read with this correction therein that the same may conform to the record of the case in the Patent Office.

Signed and sealed this 9th day of November, A. D. 1943.

Henry Van Arsdale,

Acting Commissioner of Patents.
